LAWRENCE J. MERSKE, OF MILWAUKEE, WISCONSIN

MERCHANDISE CONTAINER

Application filed June 11, 1928. Serial No. 284,516.

This invention relates to a merchandise container. The object of the invention is to provide a merchandise container having an order blank secured therein to facilitate ordering or reordering merchandise.

According to the invention, an order blank is detachably secured inside of a box and constitutes a flap to cover the merchandise contained therein.

10 A container embodying the invention is illustrated in the accompanying drawing.

The container comprises a box having a lower part 1 to contain merchandise, an upper part or cover 2 and an order blank 3 which constitutes a flap to cover the merchandise.

The order blank 3 is attached to the inside of the box and provided with perforations 4 to permit ready removal thereof.

20 Preferably, one edge of the order blank 3 is attached to one side of the bottom part 1 and the perforations 4 arranged along that edge.

The invention herein set forth is susceptible of various modifications without departing from the scope thereof as hereafter claimed.

The invention is hereby claimed as follows:

30 1. A merchandise container comprising a box, and an order blank fastened along one edge to the inside of said box to cover the contents thereof and having perforations along said edge.

35 2. A merchandise container comprising a box having a lower part to contain merchandise and an upper part to enclose the same, and an order blank detachably secured to said lower part and serving as a flap to cover the contents thereof.

In witness whereof, I have hereunto subscribed my name.

LAWRENCE J. MERSKE.
